UNITED STATES PATENT OFFICE.

HIRAM E. BARBER, OF SHERIDAN, WYOMING.

SHARPENER FOR KNIVES AND THE LIKE.

1,360,998.

Specification of Letters Patent. Patented Dec. 7, 1920.

Application filed July 9, 1919. Serial No. 309,561.

To all whom it may concern:

Be it known that I, HIRAM E. BARBER, a citizen of the United States, residing at Sheridan, in the county of Sheridan, State 5 of Wyoming, have invented a new and useful Sharpener for Knives and the like; and I do hereby declare the following to be a full, clear, and exact description of the invention, such as will enable others skilled in 10 the art to which it appertains to make and use the same.

The present invention relates to a sharpener for knives and other blades, and has for an object to provide a relatively simple 15 and economically constructed device which may be easily handled, and which requires no turning of cranks, gear wheels or other costly parts which easily get out of repair.

The invention has for another object the 20 provision of an improved guiding means for a sharpener adapted to receive a blade and hold the same in proper position for sharpening opposite sides of the blade, and for presenting different portions of an abrasive 25 surface against the opposite sides of the blade by merely drawing the latter lengthwise through the guiding means.

With these and other objects in view, the 30 invention consists in certain novel combinations and arrangements of the parts as will more fully appear as the description proceeds, the novel features thereof being pointed out in the appended claims.

For a full understanding of the invention, 35 reference is to be had to the following description and accompanying drawings, in which:—

Figure 1 is a side elevation partly in section of a knife sharpener constructed in accordance with the present invention and as applied to the edge of a table.

Fig. 2 is a vertical section taken on the line 2—2 of Fig. 1.

Fig. 3 is a horizontal section taken on the line 3—3 of Fig. 1.

Fig. 4 is a side elevation of the knife sharpener, illustrating its manner of use when held in the hand.

Corresponding and like parts are referred 50 to in the following description and indicated in all the views of the drawings by the same reference characters.

Referring to the drawing the sharpener comprises a frame 10 which is substantially

U-shaped having the opposed arm portions 55 11 and 12, the latter constituting the base or bottom of a casing 13 which projects from the frame and forms a part thereof. The arm 11 of the frame is provided with a clamping screw 14 having a swiveled head 60 15 on its inner end toward the arm 12, and provided upon its outer or other end with a handle 16 adapted for use in turning the screw 14 for clamping the sharpener in position, and also for use in supporting the 65 sharpener should it be desired to temporarily hold the same in the hand.

The casing 13 is provided with an abrasive roller 17 which is of substantially spool construction and provided with inner opposed frusto-conical sharpening faces 18 and mounted upon a shaft or spindle 19 which has bearing in the opposite sides of the casing 13.

The casing 13 is provided at one side with 75 a diagonally extending guiding groove or slot 20 adapted to receive therein a knife blade, such as at 21, and to hold the blade with one side against one of the faces 18 and the other side against the opposite face 18. 80 The knife 21 may thus be held in contact with the opposed faces of the abrasive roller, and the latter may be rotated by movement of the knife 21 in a lengthwise direction through the diagonal slot 20 so as to present 85 a continuously changing abrasive surface to the opposite sides of the knife edge.

The casing 13 is provided at one side, preferably adjacent one end of the slot 20, with a pair of outwardly extending lugs 22 90 which may be employed for bracing the casing during use, and which, as shown in Fig. 4, may be employed as rests upon which the device may be supported near the edge of a table when the device is held by the handle 16.

In use, the frame of the device may be clamped upon the edge of a table 23, or the like, as shown in Fig. 1, and secured rigidly in position by turning the handle 16 and 100 binding the swiveled head 15 against the under side of the table 23. When in this position, a knife blade may be quickly and easily fitted into the slot 20. The opposite sides of the knife blade rest against the 105 opposed grinding surfaces 18. The knife may now be drawn lengthwise through the slot and upon such movement the abrasive

roller 17 is turned and, by virtue of the diagonal positioning of the knife blade 21, the grinding faces 18 are caused to frictionally rub against the opposite sides of 5 the edge of the blade to effectively and simultaneously grind said opposite sides.

By arranging the guide 20 obliquely or diagonally across the side of the casing 13, a two-fold result is accomplished, namely, 10 the blade is sharpened simultaneously at opposite sides, and second the grinding surfaces 18 are caused to frictionally rub against the opposite sides of the blade while at the same time the rotary movement is 15 imparted to the roller 17.

If it is desired to temporarily hold the sharpener in position for use, it may be held in the hand by grasping the handle 16 and the lugs 22 may be fitted over the edge 20 of a table to support the casing 13 against the thrust and draw of the knife 21 or other blade which may be fitted in the guide 20. The rear side of the casing 13 forms a shoulder engaging the edge of the table or shelf 25 and holds the device from slipping over the surface of the table should pressure be exerted upon the handle 16 to slide the device away from the operator.

Having thus described the invention, what

I claim as new and desire to secure by Letters Patent, is:—

1. A knife sharpener including a frame provided with a clamp, a handle projecting from the clamp and providing a means for manipulating the frame, a casing carried by the frame, abrading means within the casing, and a lug projecting from the device and adapted to form a rest for co-operation with the handle to steady the sharpener when it is not clamped in position. 40

2. A knife sharpener including a U-shaped frame, a clamping screw threaded in one of the arms of the frame, a handle applied to the clamping screw, a casing carried by the other arm of the frame, an abrading wheel 45 within the casing, and a lug projecting from the casing and adapted to form a rest for co-operation with the handle to steady the device when it is used without being clamped in position. 50

In testimony whereof I have signed my name to this specification in the presence of two subscribing witnesses.

HIRAM E. BARBER.
